Alexander Brey

ATTORNEY

UNITED STATES PATENT OFFICE.

MAX EHRENFIELD, OF NEW YORK, N. Y.

CUFF-LINK.

1,362,402.

Specification of Letters Patent. Patented Dec. 14, 1920.

Application filed July 17, 1920. Serial No. 396,949.

To all whom it may concern:

Be it known that I, MAX EHRENFIELD, a citizen of the United States, residing at New York city, in the county and State of New York, have invented new and useful Improvements in Cuff-Links, of which the following is a specification.

This invention relates to improvements in links for connecting buttons, the same being designed for use in connection with cuffs or bands on shirt sleeves, particularly of the non-starched or non-stiffened variety now in common use, and for other analogous uses and purposes for which it may be adapted.

A main object of the invention is the provision of a cuff link of simple, efficient and durable construction, and one with which buttons, differing either in size or shape, may be employed, it being the purpose to fashion and arrange the parts in such manner that the buttons may be readily attached to or secured on the link and as readily removed therefrom.

Another object of the invention is to provide an elongated link having, as a novel feature of improvement, a pivoted side, which, when moved into open position, will permit either the application or removal of the buttons, and which, when moved into closed position, will serve as means for keeping the buttons separated, with one operatively held or maintained at each end of the link.

A further object is to provide in coöperation both with the link and the pivoted or movable side, means whereby the latter may be maintained either in open or closed position.

Other objects and advantages will appear in the following description, and the invention will be particularly defined in the claims hereto appended.

In the accompanying drawing, forming a part of this application;

Figure 1 is a sectional end view of a shirt sleeve cuff, showing my improved link applied thereto.

Fig. 2 is a side elevational view of the link, showing the pivoted side in closed position, parts being in section.

Fig. 3 is a similar view, with the pivoted side in open position.

Fig. 4 is a section on the line 4—4 of Fig. 2.

Fig. 5 shows a section on the line 5—5 of Fig. 2.

Fig. 6 is an enlarged fragmental view in perspective of a curved end.

Referring to the accompanying drawing by numerals, 7 represents in general a one-piece elongated link, made from gold or silver or any suitable alloy thereof, or of any suitable material plated with gold or silver. This link is of the same thickness throughout and has its opposite ends curved or bowed in plan toward each other as shown at 8 and 9, the curves being precisely alike and the extent thereof being somewhat greater than a semi-circle. The free ends 10 and 11, respectively, of the curves or bows 8 and 9 project toward each other in plan, and the same are reduced on opposite sides so as to fit snugly between the side plates 12 and 13 of the U-shaped member 14, the extent of such reductions being substantially equivalent to the thickness of said side plates, so that the outer surfaces of the side plates will come even with the outer surfaces of the bows and as well with the connecting straight portion 15. 16 is a rivet or pivot which extends transversely through the side plates 12 and 13 and also through the reduced end 10, whereby pivotally to connect the U-shaped member 14 with the curved or bowed portion 8. The opposite ends of said side plates are preferably curved toward each other as at 17, and these plates are of such width that they meet the straight portion 15 when the U-shaped member is closed as shown in Fig. 2.

In order to maintain the U-shaped member either in closed position as shown in Fig. 2, or in open position as shown in Fig. 3, I provide a cam-like device or catch 18, disposed between the side plates 12 and 13, and held in position by a rivet extending through a half eye 20, provided on the inner edge 21, adjacent the end remote from the pivot 16. Adjacent the pivot 16, the catch 18 is made with a pointed or cam portion 22 having on its outer side a straight edge 23, designed to engage and work on the end and inner side of the reduced portion 10. Under this arrangement, the U-shaped member 14 may be readily moved from closed position to open position or from open position to closed position, and will be maintained in either position through the coöperation of the cam portion 22 with the reduced portion 10.

24 and 25 represent buttons, provided each with an eyed shank 26, whereby to be swung on the link 7, the buttons being of

course introduced on the link at the reduced portion 11 thereof when the U-shaped member has been moved into open position. One button is moved to swing from each 5 curved or bowed end 8 and 9, after which the U-shaped member is closed, thereby keeping the buttons separated, and maintaining them in position to be passed through the button-holes 27 and 28 of the cuff 29. The buttons being removable from the link, can be exchanged either for larger or smaller buttons as may be necessary best to meet conditions in respect of the size of the button-holes or of other adaptations of 10 use.

Having thus described my invention, what I claim is:—

1. The herein described cuff link comprising an elongated link having a straight portion connecting bowed portions terminating in reduced ends projecting toward each other in plan, a U-shaped member pivotally engaged with one reduced end and of a length to reach and engage the other 25 reduced end and of a width to meet the straight portion, and means arranged in the U-shaped member and adapted to coöperate with the reduced end containing the pivot whereby to maintain the U-shaped member 30 either in open or closed position.

2. The herein described cuff link comprising a one-piece elongated link of the same thickness throughout and having a straight portion connecting bowed portions terminating in reduced ends projecting toward each other in plan, a U-shaped member pivotally engaged with one reduced end and of a length to reach and engage the other reduced end and of a width to meet the 35 straight portion, said U-shaped member being of the same thickness as said link, and a cam device disposed in the U-shaped member and adapted to coöperate with the reduced end containing the pivot whereby to maintain the U-shaped member either in open or closed position.

3. In a cuff link, the combination with a one-piece link having a straight portion connecting two outwardly bowed portions

terminating in reduced ends that project 50 toward each other, of a U-shaped member pivotally engaged with one of the reduced ends and of a length to reach and engage the other reduced end and of a width to meet the straight portion, and means arranged in the U-shaped member and adapted to coöperate with the reduced end containing the pivot whereby to maintain the U-shaped member either in open or closed 55 position.

4. In a cuff link, the combination with a one-piece link having a straight portion connecting two outwardly bowed portions terminating in reduced ends projecting toward each other in plan, of a U-shaped member 60 pivotally engaged with one of the reduced ends and of a length to reach and engage the other reduced end and of a width to meet the straight portion, a rivet 65 connecting the sides of the U-shaped member, and a plate disposed in the U-shaped member and having a half eye fitting on said rivet, said plate having a cam projection designed to coöperate with the reduced end containing the pivot whereby to maintain the U-shaped member either in open or closed 70 position.

5. In a cuff link, the combination with a one-piece link having a straight portion connecting two outwardly bowed portions 75 terminating in reduced ends that project toward each other in plan, of a U-shaped member pivotally engaged with one of the reduced ends and of a length to reach and engage the other reduced end and of a width 80 to meet the straight portion, a button swung on each outwardly bowed portion, and means arranged in the U-shaped member and adapted to coöperate with the reduced end containing the pivot whereby to maintain the U-shaped member either in open or closed 85 position, said U-shaped member when closed serving as means for keeping the buttons separated.

In testimony whereof I have signed my name to this specification.

MAX EHRENFELD.
